TO HENRY GREGORY BARNHURST, OF CATASAUQUA, PENNSYLVANIA.

METHOD OF BURNING POWDERED FUEL.

961,672.

Specification of Letters Patent. Patented June 14, 1910.

Application filed January 21, 1910. Serial No. 539,402.

To all whom it may concern:

Be it known that I, HENRY R. BARNHURST, a citizen of the United States, residing at Allentown, county of Lehigh, State of Pennsylvania, have invented certain new and useful Improvements in Methods of Burning Powdered Fuel; and I do hereby declare the following to be a full, clear, and exact description of the invention, such as will enable others skilled in the art to which it appertains to make and use the same.

My invention relates to improvements in effecting the combustion, for industrial purposes, of fuel of such a character that ordinary expedients for burning it are attended with but indifferent results.

One of the materials for whose combustion the invention is particularly intended is anthracite culm, that is to say, the fine screenings and other refuse from coal mining operations, which have accumulated in large quantities in the neighborhood of coal mines and coal breakers, and including the still more finely divided anthracite mud constituting the tailings of coal washeries.

The smaller sizes of anthracite coal are to a greater or less extent recoverable as such from the culm, by various separating operations, and appear on the market under the names of "buckwheat", "ricey" and "barley"; but this separation is not always commercially feasible, and even when practiced, there is always left a large residue, consisting of finer particles of anthracite, carrying a considerable percentage of ash-producing constituents, which residue, in so far as I am aware, has not heretofore been successfully utilized as a fuel, although its percentage of combustible matter is sufficient to constitute it a valuable fuel were it properly and completely burned. By the practice of my invention, it is feasible to burn this culm, whether with or without the preliminary separation therefrom of the smaller sizes of coal above specifically referred to, and in spite of the fact that, unlike ordinary bituminous coal, it contains comparatively little ignitable hydrocarbon.

In the practice of my invention, I first grind the anthracite culm in a dry condition, to an exceedingly fine powder, the grinding operation preferably reducing it to such a minute degree of subdivision that say 85% of the mass would pass through a screen of No. 200 mesh. By the aid of an

air current of sufficient pressure, the finely pulverized and difficultly ignitable culm is injected into my combustion chamber in the form of a fuel cloud, and under such conditions that the cloud-like body as it enters the combustion chamber travels in close proximity to a highly heated "ignition" surface (preferably the lower surface of the arch of the combustion chamber) where it is ignited. It then returns upon itself in the form of a loop, the outgoing branch of the loop radiating its heat upon the incoming branch in process of ignition, and preferably taking its exit from the combustion chamber in such manner that the products of combustion will envelop the conduit through which the mixture of the pulverized culm and air is injected. This intersection of the products of combustion with the conduit through which the fuel cloud enters tends to correspondingly preheat the latter, and has the additional function that at this point a minor portion of the products of combustion is entrained with and joins the incoming branch of the loop thereby assisting in its deflagration by adding to the fuel cloud the sensible heat of the combustion products thus entrained. Finally, the main body portion of the products of combustion, on leaving the combustion chamber traverses the reverse side of the "ignition" wall or arch above referred to, thereby transmitting therethrough to the entering fuel cloud such a large amount of heat that, in practice, it is found that effective ignition or deflagration of the fuel and its ultimate practically complete combustion can be relied upon.

In the accompanying drawing, I have illustrated a form of apparatus which I have found well adapted for the practice of my invention, and which, in operation, embodies my preferred plan for carrying it into effect.

In the drawing, Figure 1 represents a longitudinal sectional view of my said preferred form of apparatus; and Fig. 2 represents a cross-sectional view thereof taken on a plane indicated by the line 2-2 of Fig. 1.

Similar letters of reference indicate similar parts in both views.

Referring to the drawing, A indicates the front outer wall of the furnace structure, B the outer side walls thereof, and C the combustion chamber. One of the walls of the

combustion chamber (preferably the arch *a* thereof) is made quite thin, say nine inches in thickness or thereabout, and of refractory material conductive to heat, (the more conductive the better), and is intended to serve as the "ignition" wall or arch hereinbefore referred to. Accordingly, the pipe *b* through which the mixture of air and pulverized culm is projected, and the surrounding conduit or twyer *c* through which an additional amount of atmospheric air is drawn in, are located just out of line with the inner surface of the wall or arch *a*, so as to direct the incoming fuel cloud along and in close proximity thereto.

At its furthermost or rear end, the combustion chamber *C* is curved, as shown, and its walls are preferably made smooth throughout so as to minimize the formation of interfering eddy currents. The exit port *d* for the products of combustion is located in proximity to the entrance conduit for the fuel cloud, and the said exit port leads into a wide and large flue *e* on the reverse or upper side of the wall or arch *a*. In this flue of large dimensions, the products of combustion are slowed down to a velocity of say 20 to 22 feet per second, and have the opportunity to impart a sufficient portion of their heat to the wall or arch *a* and therethrough to the entering fuel cloud to raise the temperature of the latter and thus to assist in continuously maintaining it at the full ignition point.

Before injecting into the combustion chamber the mixture of air and pulverized culm, I heat the combustion chamber to such a degree and in such manner as will bring it to the temperature necessary to initiate the ignition and combustion of the mixture of air and pulverized culm which would otherwise not ignite. While this preliminary heating of the combustion chamber may be effected in various ways, such as by making therein a wood fire, I find that it may be quickly and conveniently brought to a high temperature by thereafter introducing, through the pipe *b*, the usual mixture of air and finely pulverized ordinary bituminous coal, which then readily ignites because of the large proportion of rich hydrocarbons present in that fuel. As soon as the combustion chamber has been sufficiently heated, and particularly as soon as the inner surface of the wall or arch *a* has been raised to the temperature necessary for insuring and maintaining ignition of the mixture of air and pulverized culm, the supply of pulverized bituminous coal is cut off and the pulverized culm is substituted therefor. The regular operation then proceeds continuously. The mixture of air and pulverized culm projected into the combustion chamber through the pipe *b* draws in an additional supply of air through the conduit *c* and is at

once ignited by the heat radiated upon it from the ignition wall or arch *a*. The ignited fuel cloud traveling rapidly along the wall or arch *a* constitutes the entrance branch of the loop. The ignition progresses from the periphery toward the center of the fuel cloud, which increasing in volume as it advances, is finally deflected by the curved or filleted rear wall of the combustion chamber and merges into the return branch of the loop, which takes its way toward the exit port *d*, in the form of a flame cloud burning fiercely by the time it reaches the front part of the combustion chamber. The heat of the flame cloud constituting the return bend of the loop is thus radiated, as the operation proceeds, upon the entering branch of the loop consisting of the continuously supplied and ignited fuel cloud of air and pulverized culm.

A portion of the products of combustion from the flame cloud is drawn into the entering fuel cloud at the point where the latter issues from the injector into the combustion chamber, thereby imparting to the fuel cloud the sensible heat of the portion of the products of combustion thus entrained. Coincident with the intense inflaming of the return bend or current of the loop, the accompanying air and products of combustion have experienced an enormous expansion, so that the flame cloud rises through the uptake in strong volume and with a velocity which is greatest at the middle of the arch *a*. Accordingly I have selected this point as the preferable point of location for the fuel injector, although it will be understood that I do not limit myself to such location, as in some instances, especially, for large furnaces, it may be found desirable to use more than one fuel injector. Finally, the main body portion of the products of combustion, issuing and passing along the wide and spacious flue *e* on the reverse side of the highly conducting thin wall or arch *a* keeps said wall or arch continuously at the high temperature necessary for the maintenance of ignition of the entering cloud of air and pulverized culm. After subserving the functions described, the products of combustion pass on to the place of use for which they are intended, as, for instance, to a steam boiler, a kiln, the laboratory of a metallurgical or heating furnace, or the like.

While I have described in detail the specific application of my invention to the waste material known as anthracite culm, yet it will be quite evident that the method described is equally applicable to other fuels of difficult ignitability which are usually, for this very reason, regarded as waste fuels, and exist at present, in enormous quantities. Such materials form at the present time a large item in the waste of our natural resources, and their efficient utilization is of

great economic and national importance. Among such materials I would enumerate coke breeze, charcoal breeze, tank mud from coal washeries, and low grade bituminous 5 dusts of difficult ignitability, containing high percentages of ash. Furthermore, it is quite within the range of practicability to pulverize the smaller sizes of anthracite coal and burn them as dust by my invention. I 10 wish, therefore, to include artificially powdered anthracite with the anthracite culm as within the scope of my invention.

Having thus described my invention, what I claim is:—

- 15 1. The method of burning anthracite culm and similar materials, which consists in raising the temperature of a combustion chamber, up to the ignition point of a body of air mixed with such material in powdered 20 form, projecting the mixture into, and along a wall of, the combustion chamber and igniting it therein, causing the products of combustion to return upon themselves within the combustion chamber, the return current radiating heat upon the incoming current, and causing the products of combustion, 25 after taking their exit from the combustion chamber, to maintain said wall at an ignition temperature at the point of discharge 30 of the fuel; substantially as described.
2. The method of burning anthracite culm and similar materials, which consists in projecting into a combustion chamber and along a highly heated ignition surface thereof a body of air mixed with such material in powdered form, thereby igniting the mixture, causing the products of combustion to return upon themselves within the combustion chamber, the return current radiating 35 its heat upon one side of the incoming current, and further heating the incoming current so as to assist in its deflagration by causing the products of combustion after 40 they leave the combustion chamber to pass along the reverse side of the highly heated ignition surface and maintaining said surface thereby at an ignition temperature at 45 the point of discharge of the fuel; substantially as described.
- 50 3. The method of burning anthracite culm

and similar materials, which consists in projecting into a combustion chamber and along a wall thereof a body of air mixed with such material in powdered form, preheating said wall up to the ignition temperature of said mixture, whereby, as the incoming current enters, it will be ignited, causing the products of combustion to return upon themselves within the combustion chamber, the return current radiating heat upon the incoming current, entraining into the incoming current a portion of the products of combustion from the return current, and continuously maintaining the preheated wall at the point of discharge of the fuel at the 55 ignition temperature for the mixture by passing the outgoing products of combustion along its reverse side after they leave the combustion chamber; substantially as described.

4. The method of burning anthracite culm and similar materials, which consists in projecting into a combustion chamber and along a wall thereof a body of air mixed with such material in powdered form, preheating said wall up to the ignition temperature of said mixture, whereby as the incoming current enters it will be ignited, causing the products of combustion to return upon themselves within the combustion chamber, the 60 return current radiating heat upon the incoming current, entraining into the incoming current a portion of the products of combustion from the return current, preheating the incoming mixture of air and fuel powder 65 by heat from the outgoing products of combustion, and continuously maintaining the preheated wall at the point of discharge of the fuel at the ignition temperature for the mixture by passing the outgoing products 70 of combustion along its reverse side after they leave the combustion chamber; substantially as described.

In testimony whereof I affix my signature, in presence of two witnesses.

HENRY R. BARNHURST.
